DEFROSTING TIMER

Richard A. Haigh, Brighton, Mich., assignor to
 Automatic Controls Corporation, Ann Arbor,
 Mich., a corporation of Michigan

Application October 15, 1949, Serial No. 121,619

7 Claims. (Cl. 161—1)

1

This invention relates to improvements in defrosting timers; that is to say clock controlled switches for breaking the operating circuits of electric refrigerators to effect automatic defrosting of the refrigerator coils.

One of the objects of the invention is the provision of novel means for reinforcing the terminal prongs by means of which the electrical connections of the unit are made and by means of which the unit is supported.

Another object is the provision of means permitting the adjustment of the twenty-four hour wheel of the unit to the time of day when the unit is installed independently of the angular position of the clock shaft.

Still another object is the provision of means accessible from the exterior of the unit casing for varying the length of the period during which defrosting takes place.

Other objects and features of novelty will appear as I proceed with the description of that embodiment of the invention which, for the purposes of the present application, I have illustrated in the accompanying drawing, in which

Fig. 1 is a plan view of the unit looking toward the cover of inverted cup shape, it being understood that the face of the cover stands in a vertical plane when the unit is attached to a wall receptacle.

Fig. 2 is a plan view partially in section along the line 2—2 of Fig. 3.

Fig. 3 is a view of the unit partially in elevation and partially in section along the line 3—3 of Fig. 1.

Fig. 4 is a large scale fragmental view with the cover removed and illustrating the Geneva motion driving means from the clock shaft to the twenty-four hour wheel.

Fig. 5 is a similar view with the parts in the open switch or defrosting position.

Fig. 6 is a detail view illustrating the means for disconnecting the Geneva motion drive when the twenty-four hour wheel is being advanced manually in the operation of setting the unit in accordance with the time of day.

Fig. 7 is a detail sectional view taken substantially on the line 7—7 of Fig. 2.

Fig. 8 is a large scale detail sectional view of the twenty-four hour wheel and associated parts.

Fig. 9 is an inverted plan view of the rotating handle-pointed corresponding to the hour hand of a twenty-four hour clock, and

Fig. 10 is an inverted plan view of the arm which moves with the pointed and is adjustable relatively thereto for varying the defrosting period.

The defrosting unit of the present invention comprises a flat base 15 upon which the working parts of the unit are mounted and a cover 16 shaped like an inverted cup and secured to the

base by means of a plurality of screws 17 which extend through openings in the base and are threaded into holes 18 formed in bosses projecting inwardly from the cover walls. The two casing parts are preferably constructed of molded plastic.

A pair of metal prongs 19 extend through the base 15 near the perimeter thereof, being preferably fixed in the base during the molding operation. These prongs have lateral offset portions 20 which engage a small ledge 21 on the base. From the upper ends of the offset portions fingers 22 project inwardly and are electrically connected to the ends of the coil 23 of a synchronous motor. The coil is wound upon a laminated core 24 which is secured to the base 15 by bolts or screws, thus holding the coil 23 firmly in place.

One of the cover bosses is provided with a pair of slots 25 which snugly receive the offsets 20 of the prongs when the cover is mounted in place. These slots may be tapered with the point of the taper uppermost so that the offsets are readily received within the slots when the cover is put in place. Because of this construction the prongs have a firm bearing not only in the base 15 but also in the cover portion of the casing at a point spaced from the first named bearing. Hence the mechanical connection of the prongs to the casing is especially strong and rigid, which is an important consideration since the prongs, in addition to making the necessary electrical connection of the unit with the house wires, serve as the support for the unit. When the unit is in use the prongs extend into a wall socket or receptacle, bringing the base 15 into a vertical plane against the receptacle or wall.

The internal construction of the unit comprises bracket means for supporting the various working parts. As illustrated herein this bracket means, which is omitted from Figs. 4 and 5 for the sake of clearness, includes an inverted sheet metal U member 27 with an extension 28 to which is attached a socket 29 that projects through a slot 30 in the cover 16 and is intended to receive the plug on the electric conductor for the refrigerator. Bracket member 27 supports the upper bearing 31 for the shaft 32 of the clock 33. Bracket member 27 also has a pair of arms 34 and 35 which support a strip of insulating material 36 upon which are carried the switch and its actuating lever presently to be described.

The bracket member 27 has attached thereto a second upwardly extending inverted U member 37 of sheet metal, the function of which is to support the upper bearing 38 for the twenty-four hour wheel 39. This wheel has a downwardly projecting shaft 40 which is journaled in the bracket member 27.

Wheel 39 is driven from shaft 32 by a Geneva motion drive of novel form. Wheel 39 is pro-

vided with twenty-four peripheral notches 41, providing twenty-four teeth 42. Surrounding shaft 32 there is a spiral spring 43 of several convolutions which normally grips the shaft closely. At its upper end it has a tangentially projecting part 44 and a downwardly extending offset arm 45 which is adapted to extend into the notches 41 of the wheel. Shaft 32 makes one revolution per hour in the counterclockwise direction as viewed in Figs. 4, 5 and 6, and once for each revolution the offset arm 45 enters one of the notches 41 and advances wheel 39 one-twenty-fourth of a revolution clockwise. 46 is a spring detent adapted to engage a notch of the wheel, this detent yielding as the offset arm 45 turns wheel 39, traveling over a tooth 42 and snapping into the next notch 41 of the wheel. Detent 46 therefore holds the wheel against accidental movement and insures its advancement the proper distance as the offset arm 45 of the spring leaves the recess with which it has been in engagement.

The shaft for wheel 39 has a large diameter portion 40' above the wheel in which there is a diametrical slot 47 for a purpose which will presently appear. Surrounding this shaft 40' there is a sleeve 48 which extends down into a cavity 49 in the wheel. Sleeve 48 has a right angle extension 50 also disposed in cavity 49. At the outer end of this extension there is a downwardly extending pin 51 which projects through a slot 52 in the wheel. A second pin 53 integral with wheel 39 projects downwardly therefrom, these two pins 51 and 53 being disposed at approximately the same radial distance from the axis of the wheel. Sleeve 48 has a pair of oppositely disposed slots 54 extending downwardly from its upper edge. The turning of sleeve 48 through a small angle from the position of Fig. 4 to that of Fig. 5 spaces the pins 51 and 53 further apart. Pin 51 is yieldably held in one or the other of its two operative positions by a small hump 55 at the mid-point of the slot, there being sufficient play in the mounting of the sleeve to permit the pin to ride over this hump when the extension 50 is swung from one position to the other.

Referring now to the switch construction illustrated herein, the insulation strip 36 is formed of stiff material so as to afford a rigid mounting for the switch parts. It supports two electric terminals 57 and 58 having electrical connections 59 and 60. Terminal 57 is permanently connected with a metallic angle post 61 which has a slot therethrough to receive the long arm of a bell crank lever 62 and form a pivot therefor. When the switch is closed this arm occupies the position illustrated in Fig. 4, in which the extremity of the short arm of the lever bears against the strip 36. A flat spring metal link 63 has a slot part way of its length which straddles post 61 and the short arm of lever 62. The end of link 63 beyond the slot bears against an indentation in the short arm of the lever. At its opposite end this link carries a contact button 64 and one extremity of a bowed spring 65, the other extremity of which rests in a notch 66 in the post 61. Spring 65 therefore functions to maintain the pivotal connection between conductor 63 and lever 62 by pushing the right hand end of the conductor toward the right as viewed in Figs. 4 and 5, and acts as an electrical conductor between button 64 and post 61.

As the pin 51 in turning step by step clockwise strikes the long arm of lever 62 and wipes against it the lever is shifted from its Fig. 4 position to

that of Fig. 5, which pulls downward flat link 63 below the notch 66. This snaps the link 63 over dead center and causes the contact button 64 to snap down against a stop 67 carried by insulation strip 36, thereby opening the circuit. Before pin 51 passes beyond the end of lever 62, pin 53 comes into contact with the lever and holds it up. When the pins are spaced as in Fig. 5 the period of their contact with the lever is of course longer than when the pins are close together as in Fig. 4. When pin 53 moves out of contact with lever 62 the spring 65 by pulling upon the short arm of the lever swings the latter to the Fig. 4 position, causing the link 63 to shift over to a position above the notch 66 which snaps the contact 64 upwardly into engagement with the terminal 58, again closing the switch.

While I have described more or less in detail a particular type of switch that is suitable for the purposes of the invention, it will be understood that any other switch capable of being actuated by a lever similar to lever 62 may be employed.

When the casing parts 15 and 16 are assembled the shaft 40' and sleeve 48 project through a hole 69 in the casing cover 16. An adjusting arm 70 shown inverted in Fig. 10 is then slipped over the sleeve 48. It is provided with two splines 71 which enter the slots 54 in the sleeve, thereby locking these two members together against relative rotation. At the outer extremity of arm 70 there is a pin 72 which projects upwardly. When the adjusting arm 70 is in place a handle-pointer 73 is slipped down over the upper extremity of shaft 40', arcuate shaped walls 74 on the handle receiving the shaft and a transverse rib 75 entering the slot 47 at the end of the shaft, thereby locking the pointer to the shaft.

At its rear end the pointer 73 has an arcuate cutout 76 which receives the pin 72 on the arm 70. At the ends of this cutout the handle-pointer bears indicia indicating the adjustment for the period of defrosting. In this case the indicia are the numbers 3 and 4 indicating defrosting periods of three and four hours respectively. In the normal operation of the device the handle-pointer 73 and the arm 70 move together step by step. On the face of the cover there are printed numbers indicating the time of day in one hour steps both a. m. and p. m.

When one of these units is to be installed the operator turns the handle-pointer 73 clockwise to the time indicated on the face of the cover which is nearest to the then time of day. If at the time this is done the offset arm 45 of spring 43 happens to be out of contact with the wheel 39, as for example in Fig. 5, the rotation of the handle merely causes the spring detent 46 to click from one notch to the next as the wheel is turned. If on the other hand the arm 45 of the spring happens to be in engagement with the wheel, as in Fig. 4, it tends to oppose rotation of the wheel. A slight additional pressure on the wheel by the operator however then unwinds spring 43 slightly, thereby loosening the grip of the spring upon shaft 32 as indicated in Fig. 6 of the drawing. After the grip is thus loosened the spring is readily turned bodily on the shaft 32 without placing any undue strain on the shaft or the clock mechanism connected thereto. It will be observed therefore that when the clock shaft is the driving member the spring tends to wind itself tightly upon the shaft, whereas when the wheel 39 is the driving member, as in setting the handle-pointer to the time of day, the spring unwinds and loosens its grip upon the shaft.

Respecting the electric circuits it will be obvious that current enters the unit through one of the prongs 19 and flows to one of the connections in the socket 29, as by the conductor 30, thence through the refrigerator cord to the refrigerator motor, back to the other connection in socket 29, through a conductor 31 to switch connection 59, through the switch to connection 60 and thence by a conductor 32 to the other prong 19. The coil 23 of the clock takes its current directly from the prongs 19, as previously described.

The operation of the device it is believed will be clear from the foregoing description of its construction. The pins 51 and 53 are so disposed with respect to the handle-pointer 73 that during the early morning hours following midnight the switch will be opened for three or four hours, as may be desired, to accomplish the defrosting operation, thereby freeing the refrigerator coils of frost and ice insulation once every twenty-four hours and enabling the refrigerator to operate at maximum efficiency.

It will be apparent that the unit is compact and sturdy, economical to manufacture and assemble, simple to install and not likely to get out of order. The provisions for adjusting it to the time of day and for varying the length of the defrosting period are particularly noteworthy and important.

Having thus described my invention, I claim:

1. In an electrical timing unit, a clock having an hour shaft rotating in a given direction, a second shaft parallel to said clock shaft, a wheel on said second shaft having peripheral notches therein, yieldable means carried by said clock shaft and projecting laterally therefrom for meshing engagement with said notches one at a time and adapted to impart intermittent rotation to said wheel in the reverse direction, a switch, means for actuating said switch comprising a projection turning with said wheel, and means for manually turning said wheel in said reverse direction, said yieldable means being adapted to yield and permit said manual turning in said reverse direction, whereby the angular position of said wheel relative to that of said clock shaft may be manually selected.

2. In an electrical timing unit, a clock having an hour shaft rotating in a given direction, a second shaft parallel to said clock shaft, a wheel on said second shaft having peripheral notches therein, means carried by said clock shaft projecting laterally therefrom for intermittent meshing engagement with said notches one at a time and adapted to impart positive step by step rotation to said wheel in the reverse direction, and means for manually turning said wheel in said reverse direction, said first named means being adapted to yield for permitting rotation of said wheel in said reverse direction, whereby the angular position of said wheel relative to that of said clock shaft may be manually selected.

3. In an electrical timing unit, a clock having a rotating hour shaft, a second shaft parallel to said clock shaft, a wheel on said second shaft having peripheral notches therein, a coil spring surrounding and gripping said clock shaft, one end of said coil spring having an offset arm adapted to enter said notches one after another for imparting intermittent motion to said wheel, a switch adapted to be actuated by said wheel as it moves through a predetermined arc, and manual means for turning said wheel in a direction for causing a notch to bear against said offset arm, unwind said spring, thereby loosening

its grip upon said shaft and turning the spring bodily on said shaft, whereby the angular position of the wheel may be changed while that of the clock shaft remains unaffected.

4. In an electric timing unit, a clock having an hour shaft rotatable in a given direction, a second shaft parallel to said clock shaft, a wheel on said second shaft having peripheral notches therein, a coil spring surrounding said clock shaft, one end of said coil spring having an offset arm adapted to enter said notches one after another for imparting intermittent motion to said wheel, the rotation of said clock shaft acting when said arm is in engagement with a notch in said wheel to wind the spring tightly on said shaft for imparting a positive rotational movement to said wheel in a direction reverse to that of said clock shaft, a switch adapted to be actuated by said wheel as it moves through a predetermined arc in said reverse direction, and manual means for turning said wheel in said reverse direction, thereby causing a notch of the wheel to bear against said offset arm, unwind said spring, thereby loosening its grip upon said shaft and turning the spring bodily on said shaft, whereby the angular position of the wheel may be changed while that of the clock shaft remains unaffected.

5. In an electric timing unit, a rotatable wheel, means for imparting intermittent rotation to said wheel, an electric switch, a movable element for actuating said switch, said element being biased toward switch closing position a pair of pins movable with said wheel adapted to engage and shift said movable element once during each revolution of the wheel to open said switch and maintain it open through a given angle of rotation of the wheel, and manual means for moving one of said pins in an arcuate path through a small angle to adjust the spacing of the pins and thereby vary the length of time during which said movable element is maintained in switch opening position.

6. An electric timing unit as defined in claim 5 comprising a sleeve surrounding said second shaft and rotatable thereon through a limited arc, said movable pin being carried by said sleeve, and an arm mounted on said sleeve manually adjustable through said limited arc.

7. In an electric timing unit, a casing, a clock having a rotating hour shaft, a second shaft parallel to said clock shaft projecting through said casing, a wheel keyed to said second shaft within the casing, Geneva motion means for imparting intermittent rotation to said wheel from said clock shaft, an electric switch, a movable element for actuating said switch, a sleeve surrounding said second shaft, a pin carried by said wheel and a pin carried by said sleeve at the same radial distance from said second shaft, said pins being adapted jointly to engage and operate said movable element once during each revolution of the wheel, a handle outside the casing keyed to said shaft, an arm outside the casing keyed to said sleeve and arranged for adjustment through a limited arc relative to said handle, and means on the handle holding said arm in adjusted position, whereby the pin on said sleeve may be adjusted relative to the pin on said wheel for regulating the length of time of actuation of said movable element and the consequent actuation of said switch.

RICHARD A. HAIGH.
